A. LANEGRAN.

Lamp Extinguisher.

No. 11,289.

Patented July 11, 1854.

Fig. 1.

Fig. 2.

UNITED STATES PATENT OFFICE.

ANDREW LANERGAN, OF BOSTON, MASSACHUSETTS.

LANTERN.

Specification of Letters Patent No. 11,289, dated July 11, 1854.

To all whom it may concern:

Be it known that I, ANDREW LANERGAN, of Boston, in the county of Suffolk and State of Massachusetts, have invented a new and useful Improvement in Lanterns; and I do hereby declare that the same is fully described and represented in the following specification and the accompanying drawings, letters, figures, and references thereof.

10 In the said drawings, Figure 1, represents a front elevation of one of my improved lanterns. Fig. 2, is a vertical section of the same.

In the said drawings, A, denotes the body 15 or case of a lantern, and B, the lamp thereof.

My invention or improvement consists in combining with the lantern a mouth tube, C, which I insert in the top of the lantern and extend downward within the chamber of the 20 lantern, and direct toward the wick of the lamp in such a manner that by a person applying his mouth to that part of the tube which projects outside of the lantern and blowing into said tube he may readily put 25 out the flame of the wick, and this without

the necessity of opening the lantern or removing the lamp therefrom as is generally required in order to put out the light thereof.

My improved lantern is especially intended to be used in cotton mills, stables, places 30 or factories where it may be considered dangerous to blow out the flame of a lamp, when such flame is uncovered, as when such takes place there is more or less liability of sparks or carbon in a state of combustion being 35 blown or dropped from the lamp, such often being productive of serious accidents or consequences.

What I claim as my invention or improvement is—

40 The combining with the lantern the mouth tube so as to enable a person to put out the flame of the lamp substantially as described.

In testimony whereof I have hereunto set my signature this twenty first day of January A. D. 1854.

45 ANDREW LANERGAN.
